UNITED STATES PATENT OFFICE.

WILLIAM L. BEALL, OF ALBION, MICHIGAN, ASSIGNOR TO THE GALE MANUFACTURING COMPANY, OF SAME PLACE.

DESIGN FOR A REVERSIBLE CUTTING EDGE FOR PLOWS.

SPECIFICATION forming part of Design No. 31,864, dated November 21, 1899.

Application filed October 17, 1899. Serial No. 733,926. Term of patent 14 years.

To all whom it may concern:

Be it known that I, WILLIAM L. BEALL, a citizen of the United States, residing at Albion, in the county of Calhoun and State of Michigan, have invented and produced a new and original Design for a Reversible Cutting Edge for Plows; and I do hereby declare the following to be a full, clear, and exact description of the same, reference being had to the accompanying drawings, forming a part thereof.

Figure 1 represents a perspective view of a cutting edge for plows embodying my design. Fig. 2 is a side elevation, Fig. 3 is a back edge view, Fig. 4 is an end view, and Fig. 5 is a transverse sectional view, of the same.

The leading feature of my design consists in the reversible cutting edge for plows, formed triangular or wedge-shaped in cross-section, the ends being indented to form a reentrant angle and the back edge and ends being oppositely beveled to form a central angular edge.

In the drawings A represents the cutting edge, being of uniform triangular or wedge shape in cross-section, as shown in Fig. 5, and having the lateral faces $a\ a$, which converge

and form an acute-angular front edge a' . The two ends of the device are provided with a reentrant angle, as indicated at $a^2\ a^2$, the sides of the angles forming acute angles with the front and back edges of the device. The back edge a^3 is parallel to the front edge and is oppositely beveled, as shown, forming the two faces $a^4\ a^4$, which extend from the lateral faces $a\ a$ in a direction away from the front edges a' to form an angular ridge. The ends of the device are also beveled oppositely, as shown, the beveled portions $a^5\ a^5$ conforming to the reentrant angles and the beveled faces decreasing in width from their juncture with the beveled faces $a^4\ a^4$ toward the front edge a' .

What I claim, and desire to secure by Letters Patent, is—

The design for a reversible cutting edge for plows, substantially as herein shown and described.

In testimony whereof I affix my signature in presence of two witnesses.

WILLIAM L. BEALL.
